United States Patent Office.

LEONARD QUETSCH, OF URBANA, ILLINOIS.

Letters Patent No. 96,036, dated October 19, 1869.

APPARATUS FOR ADMINISTERING MEDICATED OR PURE STEAM TO BRUTES.

The Schedule referred to in these Letters Patent and making part of the same.

To all whom it may concern:

Be it known that I, LEONARD QUETSCH, of Urbana, in the county of Champaign, and in the State of Illinois, have invented certain new and useful Improvements in "Veterinary Steamers," and do hereby declare that the following is a full, clear, and exact description thereof, reference being had to the accompanying drawings, and to the letters of reference marked thereon, forming a part of this specification, and which represent a side elevation, part in section, of my steamer.

The nature of my invention consists in the construction and general arrangement of a steam-apparatus for generating pure or medicated steam, to be applied for the purpose of producing perspiration, or for inhalation by horses, cattle, &c., that are diseased.

In order to enable others skilled in the art to which my invention appertains, to make and use the same, I will now proceed to describe its construction and operation.

A represents a steam-boiler, of suitable dimensions to generate the necessary quantity of gas, which is placed on top of a furnace, B, the whole being portable, so as to be readily moved from one place to another, wherever needed.

On the side of the boiler A is attached a thermometer, C, to determine the exact temperature of the fluid in the boiler.

From the centre of the top of the boiler, a flexible pipe, D, leads to any point desired; and to this pipe a stop-cock may be attached, so as to regulate the delivery of the steam, which may either be in its pure state, or medicated by the addition of herbs, chemicals, or other suitable ingredients.

For inhalation, the pipe D is to be attached to a jack fastened around the mouth and lower part of the head of the animal.

To produce perspiration, the animal is entirely covered with a full supply of blankets except the head, which is left free. The steam from the boiler is then conducted under the covering by means of the flexible pipe D, or its connections.

By this means steam can be easily administered to animals, either outwardly or inwardly.

Having thus fully described my invention,

What I claim as new, and desire to secure by Letters Patent, is—

The arrangement of the boiler A, furnace B, thermometer C, and flexible pipe D, all substantially as and for the purposes herein set forth.

L. QUETSCH.
